2 Sheets-Sheet 2

<img alt="Technical drawings of a mechanical device, likely a lock or fastener, showing three views: Fig. 5 (top view), Fig. 4 (side view), and Fig. 3 (cross-sectional view). Fig. 5 shows a cylindrical body with a threaded shank (18) and a cap (21). Fig. 4 shows the shank with internal parts labeled 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, CALIPER FOR USE WITH A MICROMETER CALIPER

David G. Way, Boxborough, Mass., assignor of one-half to George J. Roderick, Wellesley, Mass.
Filed Nov. 3, 1961, Ser. No. 150,020
10 Claims. (Cl. 33—143)

My present invention relates to a caliper for use with a micrometer caliper.

Micrometer calipers are widely used in measuring outside dimensions and the smallest of these, enabling measurements up to one inch to be made, is commonly the first precision measuring tool acquired by a mechanic and has the feature that its accuracy can always be checked by determining whether or not a "zero" reading exists when its contacts are in mutual engagement. A series of micrometer calipers is required, however, to permit measurements to be made through a wide range unless other types of measuring instruments, such as a vernier caliper, are used and such are expensive and difficult to use accurately.

There is, accordingly, a demand for a caliper, particularly one for use in taking both inside and outside measurements, that combines relatively low cost with adaptability for use with a micrometer caliper, particularly the small size above referred to, thus to enable a wide range of measurements to be easily and accurately made. The provision of such calipers is the principal objective of this invention.

In accordance with the invention that objective is attained by providing a caliper that is for use with a micrometer caliper and that comprises a beam, first and second arms movable along the beam with means provided for establishing a plurality of equally spaced positions of the first arm along the beam and with the second arm being infinitely adjustable along the beam and capable of total adjustment at least as great as the spacing between each two proximate positions of the first arm. The beam and the second arm each have an anvil and these are so arranged and disposed that their spacing decreases from a predetermined far-apart position to a predetermined close-together position as the second arm is moved towards the first arm. The anvils have opposed faces the distance between which is measurable by a micrometer caliper through a predetermined range including the predetermined positions. The distance between each two proximate positions of the first arm is within that range.

In use, the two arms are adjusted to engage the work by first setting the first arm in the appropriate one of its positions along the beam and then making the fine adjustment by moving the second arm. By using a separate measuring scale, the distance between the measuring faces of the arms and the micrometer caliper reading, as measured over the anvils, can be combined to give the exact dimension that is sought. It is preferred, however, to avoid the use of a separate measuring scale, and to use indicia on the beam that are so arranged that the micrometer caliper reading may be added directly to the indicia associated with the position of the first arm to give the exact dimension sought with maximum convenience.

Other general objectives are concerned with the anvils and their attachment to the beam and to the second arm, with the adjustment of the relation of the anvil faces to each other, with the construction of the bases of the arms, and with the relative dimensions of the anvils and work engaging contacts relative to the spacing between each two proximate positions of the first arm.

In the accompanying drawings, there is shown an illustrative embodiment of the invention from which

2

these and other of its objectives, novel features, and advantages will be readily apparent. In the drawings,

FIGURE 1 is a top plan view of a caliper in accordance with the invention,

5 FIGURE 2 is a side view thereof indicating its use in making an outside measurement with the fine adjustment being measured by an indicated micrometer caliper,

FIGURE 3 is a section, on an increased scale, taken approximately along the indicated lines 3—3 of FIGURE

10 1, and

FIGURES 4, 5 and 6 are sections, on the scale of FIGURE 3, taken approximately along the indicated lines 4—4, 5—5, and 6—6, respectively, of FIGURE 2.

In accordance with the invention, a beam 10 supports 15 the generally indicated bases 11 and 12 of the arms 13 and 14, respectively. The arms 13 and 14 are provided, adjacent their ends, with aligned inwardly disposed contacts 15 for use in taking outside measurements, such as measuring the diameter of the indicated shaft S. The 20 contacts 15 include outwardly disposed ends 15a for engaging the work when inside measurements are wanted. Preferably the arms 13 and 14 are of sufficient length to ensure that, for example, they may so straddle the largest shaft that can be measured with the caliper as to bring 25 their contacts 15 into contact therewith at diametrically spaced points. The beam 10 is shown as having a series of equally spaced notches 16 along one of its edges. These are shown as spaced one-half of an inch from each other, although, in terms of metric measurements, the 30 spacing from each other would be ten millimeters, for example.

The base 11 consists of plates 17 and 17a joined to the 35 arm 13 and to a mount 18 as by rivets 17b. The end of the arm 13 joined to the plates 17 and 17a terminates in a pair of spaced beam-engaging bearings 13a. The mount 18, see FIGURE 5, has a bore 19 in communication with the notched beam edge in a zone between the bearing 13a and the bore 19 receives an anchor 20 whose beam-engaging end portion 20a is tapered to seat in any notch and to 40 be held against being wedged therefrom, on relative movement between the base 11 and the beam 10, by means of a screw 21 threaded into the outer part of the bore 19, thus enabling the base 11, and accordingly the arm 13, to be securely locked in any selected position. It will be 45 noted, see FIGURE 5, that the anchor portion 20a is rectangular, in cross section, and engaged by the sides 17 and 17a. A side of the beam 10 is provided with measuring indicia appropriate for each notch 16 and it will be noted that the base 11 has circular ports 22 and 23 whose 50 centers are shown as spaced one inch apart with the left hand one, the port 22, being used when outside measurements are being made and the number visible in the right hand one, the port 23, being used when inside dimensions are being taken.

55 The base 12 consists of plates 24 and 24a joined to the arm 14 and the mount 25 as by rivets 24b with the plates 24 and 24a extending beyond the proximate end of the beam 10. The end of the arm 14 that is joined to the base 12 terminates in a pair of spaced, beam edge 60 engaging bearings 14a. The mount 25 has a bore 26 in which there is a pair of oppositely disposed headed studs 27 urged apart by a spring 28 with one head engaging an edge of the beam 10 in a zone between the bearings and the other engaged by a screw 29 threaded in the upper part of the bore 26, thus to provide adjustable frictional 65 resistance to the movement of the base 12 relative to the beam 10. By advancing the screw 29, the studs 27 may be brought into end-to-end contact providing a positive lock against such movement of the base 12.

70 The end of the beam 10 within the base 12 has a member 30 attached thereto by screws 31 and exposed

beyond the unnotched edges of the beam 10 with the end 32 extending beyond the notched beam edge and machined to provide a first anvil face 32a. A knurled head 33 of an adjusting screw 34 threaded through one of the arm bearings 14a has a stud 35 journalled in the member 30 and the head 33 is backed thereby and confined by a shoulder 36 in the unnotched beam edge. The head 33 is exposed so that it may readily be engaged and rotated by the user in one direction or the other thereby to adjust the position of the base 12 of the arm 14 relative to the beam 10 and to the base 11 of the arm 13 as required.

Between the ends of the sides 24, 24a of the base 12 there is a member 37 having a portion 38 that extends beyond the notched beam edge adjacent the anvil 32 and is machined to establish it as a second anvil face 38a. The member 37, as may be seen in FIGURE 6, is provided with transverse bores 39 dimensioned to be slightly oversize relative to the threaded sleeves 40 of which there is one in each bore. Each sleeve 40 receives a pair of screws 41, one for each side 24, 24a and extending through a hole 42 therein the diameter of which is the wire size of the screws 41. With this arrangement, small but important adjustments can be made of the position of the member 37 to ensure that the anvil faces 32a and 38a are parallel and spaced apart the desired distance.

It will be noted that the proximate faces of the members 30 and 37 are not parallel, the face 38b of the member 37 being shown as inclined slightly away from the proximate face of the member 30 so that the parallel disposition and the spacing of the anvil faces may be facilitated by the use of a carefully machined taper, not shown, that can be inserted between said proximate faces.

It will be apparent from FIGURES 2 and 3 that the second arm base 12 is infinitely adjustable along the beam 10 through a distance at least as great as and preferably somewhat more than the spacing between each two proximate position-establishing notches 16. It will also be noted that the spacing of the anvil faces 32a and 38a decreases from a predetermined far-apart position to a predetermined close-together position as the second arm is moved towards the first arm. The distance between the anvil faces 32a and 38a is measurable with a micrometer caliper, such as the micrometer caliper M, through a predetermined range including the predetermined anvil positions referred to and the distance between each two proximate notches 16 is, of course, within that range. Because one inch micrometers are so commonly used the caliper is shown and described as constructed and adjusted for use therewith. For metric measurements, a micrometer caliper having a measuring capacity up to twenty-five millimeters is the most commonly owned so that a caliper for use therewith is preferred.

The indicia on the beam are so arranged that the figure presented by the window 22, in the case of an outside dimension, or the figure exposed in the window 23, in the case of an inside dimension, can have the reading of the micrometer caliper added directly thereto to provide the wanted measurement.

As this means that a distance equal to the close-together spacing of the anvil faces 32a and 38a is included, this factor dictates the arrangement of the indicia, and it is also essential that the length of each contact 15, including its portion 15a, be equal to the distance between each two proximate notches 16.

From the foregoing, it will be apparent that calipers in accordance with the invention are well adapted for use in meeting all requirements attendant the taking of both inside and outside dimensions through a wide range.

What I therefore claim and desire to secure by Letters Patent is:

1. In a caliper for use with a micrometer caliper,
  - (a) a beam,
  - (b) first and second arms movable along said beam,

- (c) means providing for a plurality of equally spaced positions of said first arm on said beam,
  - (d) said second arm being infinitely adjustable along said beam and capable of total adjustment at least as great as the spacing between each two proximate positions of said first arm, and
  - (e) a pair of anvils, one carried by said beam and the other carried by said second arm with their spacing decreasing from a predetermined far-apart position to a predetermined close-together position as said second arm is moved towards said first arm, said anvils including opposed faces the distance between which are measurable by said micrometer caliper through a predetermined range including said predetermined positions,
  - (f) the distance between each two proximate positions of said first arm being within said range.
2. The caliper of claim 1 in which the anvil of the second arm is adjustable relative thereto and to the beam anvil to enable their faces to be disposed in parallel and a predetermined distance apart at a predetermined setting of the second arm on the beam.
  3. The caliper of claim 2 in which the proximate face of one anvil is inclined downwardly away from the proximate face of the other anvil.
  4. In a caliper for use with a micrometer caliper,
    - (a) a beam,
    - (b) first and second arms movable along said beam,
    - (c) means providing for a plurality of equally spaced positions of said first arm on said beam,
    - (d) said beam having measuring indicia for measuring said positions,
    - (e) said second arm being infinitely adjustable along said beam and capable of total adjustment at least as great as the spacing between each two proximate positions of said first arm, and
    - (f) a pair of anvils, one carried by said beam and the other carried by said second arm with their spacing decreasing from a predetermined far-apart position to a predetermined close-together position as said second arm is moved towards said first arm, said anvils including opposed faces the distance between which are measurable by said micrometer caliper through a predetermined range including said predetermined positions,
    - (g) the distance between each two proximate positions of said first arm being within said range, but greater than the spacing of the anvils' faces in said predetermined close together position of said anvils,
    - (h) said indicia being arranged to enable the reading of the micrometer caliper, as taken from face-to-face of the anvils, to be added thereto in determining the dimension that is sought.
  5. In a caliper for use with a micrometer caliper,
    - (a) a beam,
    - (b) first and second arms movable along said beam, each arm including a work engaging contact transversely aligned with the contact of the other arm and said contacts being inwardly disposed to receive work between them, said contacts including outwardly disposed portions for inside measurements,
    - (c) means providing for a plurality of equally spaced positions of said first arm on said beam,
    - (d) the length of each contact being equal to the distance between any two proximate positions,
    - (e) said beam having measuring indicia on one face for measuring said positions,
    - (f) said second arm being infinitely adjustable along said beam and capable of total adjustment at least as great as the spacing between each two proximate positions of said first arm, and
    - (g) said first arm having a pair of windows through each of which different indicia are exposed in any of said positions, one window being for use when

making inside measurements and the other being for use in making outside measurements, the centers of said windows being spaced apart a distance equal to twice the length of each work engaging contact,

(h) a pair of anvils, one carried by said beam and the other carried by said second arm with their spacing decreasing from a predetermined far-apart position to a predetermined close-together position as said second arm is moved towards said first arm, said anvils including opposed faces the distance between which are measurable by said micrometer caliper through a predetermined range including said predetermined positions,

(i) the distance between each two proximate positions of said first arm being within said range.

6. In a caliper for use with a micrometer caliper,

(a) a beam,

(b) first and second arms movable along said beam,

(c) means providing for a plurality of equally spaced positions of said first arm on said beam,

(d) said second arm being infinitely adjustable along said beam and capable of total adjustment at least as great as the spacing between each two proximate positions of said first arm,

(e) a member attached to the beam end proximate to the second arm and including a portion protruding beyond an edge of said beam and constituting an anvil, and

(f) said second arm including a pair of sides extending beyond said member, and a second member attached to said sides and including a portion protruding beyond said beam edge and constituting a second anvil,

(g) the spacing of said anvils decreasing from a predetermined far-apart position to a predetermined close-together position as said second arm is moved towards said first arm, said anvils including opposed faces the distance between which are measurable by said micrometer caliper through a predetermined range including said predetermined positions,

(h) the distance between each two proximate positions of said first arm being within said range.

7. The caliper of claim 6 in which the second member has transverse bores, an interiorly threaded sleeve is a loose fit in each bore, and clamping screws carried by said sides are threaded in said sleeves.

8. In a caliper for use with a micrometer caliper,

(a) a beam provided with a shoulder adjacent one end,

(b) first and second arms movable along said beam,

(c) means providing for a plurality of equally spaced positions of said first arm on said beam,

(d) said second arm being infinitely adjustable along said beam and capable of total adjustment at least as great as the spacing between each two proximate positions of said first arm,

(e) a member attached to said beam end proximate to the second arm and including portions extending beyond the edges of said beam, one portion constituting a first anvil,

(f) said second arm including a pair of sides extend-

ing beyond said beam end, and a second member attached to said sides and including a portion extending beyond a beam edge near said first anvil and constituting a second anvil,

(g) the spacing of said anvils decreasing from a predetermined far-apart position to a predetermined close-together position as said second arm is moved towards said first arm, said anvils including opposed faces the distances between which are measurable by said micrometer caliper through a predetermined range including said predetermined positions,

(h) and a threaded connection between the other portion of said first member and said second arm and including a rotatable member confined between said shoulder and said other portion.

9. In a caliper for use with a micrometer caliper,

(a) a beam including an anvil at one end,

(b) first and second arms, each arm including a pair of spaced bearing portions for engagement with one edge of said beam, a mount adjacent the other edge of said beam, and sides interconnecting each arm and the appropriate mount, each mount including a movable member for engaging said beam in a zone intermediate said bearing portions,

(c) means providing for a plurality of equally spaced positions of said first arm on said beam,

(d) said second arm being infinitely adjustable along said beam and capable of total adjustment at least as great as the spacing between said positions of said first arm,

(e) the sides connected to the second arm including portions extending beyond said anvil, and a second anvil secured to said sides,

(f) the spacing of said anvils decreasing as said second arm is moved towards said first arm from a predetermined far-apart position to a predetermined close-together position, said anvils including opposed faces the distances between which are measurable by said micrometer caliper through a predetermined range including said predetermined positions,

(g) the distance between each two proximate positions of said first arm being within said range.

10. The caliper of claim 9 in which the movable member associated with the second arm includes an adjusting screw, a pair of studs disposed with one stud head engaged by the adjusting screw and the other stud head in engagement with a beam edge, and a coil spring confined between the stud heads and yieldably urging them apart, said studs being entrant of opposite ends of said coil spring and engaging one another before said spring is fully compressed.
